[57] CLAIM

The ornamental design for a handle of precision screwdriver, as shown and described.

DESCRIPTION

FIG. 1 is a perspective view of a handle of precision screwdriver showing my new design;
FIG. 2 is a front elevational view thereof; with the rear side being a mirror image of that shown;
FIG. 3 is a left side elevational view thereof; with the right side being a mirror image of that shown;
FIG. 4 is a top side elevational view thereof;
FIG. 5 is a bottom side elevational view thereof; and,
FIG. 6 is a perspective view thereof, wherein the broken line showing of the blade is for illustrative purpose only and form no part of the claimed design.
